UNITED STATES PATENT OFFICE.

ARTHUR DRESCHER, OF NEW YORK, N. Y.

PORTABLE ELECTRIC LAMP.

SPECIFICATION forming part of Letters Patent No. 623,656, dated April 25, 1899.

Application filed January 27, 1899. Serial No. 703,526. (No model.)

To all whom it may concern:

Be it known that I, ARTHUR DRESCHER, a citizen of the United States, residing in the city of New York, in the borough of Manhattan and State of New York, have invented 5 certain new and useful Improvements in Portable Electric Lamps, of which the following is a specification.

This invention relates to improvements in 10 portable electric lamps; and the objects of the invention are to provide means for protecting the incandescent bulb from breakage while in use, means for suspending the bulb, and means for conveniently handling the bulb without 15 abrasion of the conducting-wires and consequent destruction of the insulation.

The invention consists of a portable electric lamp comprising a flexible handle provided with a bore for the conducting-wires, 20 said handle being composed of a socket portion, a handle portion, and a tapering end portion, a lamp-socket in said socket portion, an incandescent electric lamp in said socket, a collar extending around the socket portion 25 of the handle, and a lamp-guard attached to said collar, and, further, in the special construction of the flexible handle and its connection with the lamp-socket and guard-frame, as will be fully described hereinafter, 30 and finally pointed out in the claims.

In the accompanying drawings, Figure 1 represents a vertical longitudinal section of a cask of large size, showing my improved portable electric lamp suspended therein. Fig. 2 35 is a side elevation of my improved lamp. Fig. 3 is a vertical central section of the same; and Fig. 4 is a bottom view on line 4-4, Fig. 2.

Similar letters of reference indicate corresponding parts.

Referring to the drawings, A indicates the 40 handle of my improved portable electric lamp. The handle is preferably made of soft rubber, so as to secure flexibility, and is composed of a socket portion, a handle portion below the same, and a tapering end portion, all made in 45 one integral piece. The handle A is provided in the handle portion and end portion with a bore for the conducting-wires, and the end portion tapers from the handle portion down 50 to the conducting-wires, as shown in Fig. 2. Into the upper or socket end of the handle A is inserted a porcelain lamp-socket C, into

which is screwed the bottom plug of an electric incandescent lamp D. One of the conducting-wires is connected to an exposed 55 metal plug at the bottom of the lamp and the other wire is connected to the metal side lining of the socket, so as to form the electrical connections in the manner common in lamp-sockets when the lamp is screwed in. The 60 upper surface of the lamp-socket is not exposed, but covered by a contracted portion of the socket portion of the handle, extending above the lamp-socket, as at a, Fig. 3, to such an extent as to hug the neck of the bulb. 65 Upon the upper end of the handle, at that portion opposite the lamp-socket, is placed a tightly-fitting collar E, which is provided at its upper end with a flange e, having a raised 70 rim e'. The flange is provided with, preferably, three key-shaped holes e², which are adapted to receive the headed ends of three correspondingly-arranged screws of the lamp-guard F. The lamp-guard F consists of the lower ring f', in which the screws f are located and which is preferably of a size to fit 75 within the raised rim e', an upper ring f², a block f³ at the apex of the guard, and a number of curved guard-wires f⁴, attached at their lower ends to the lower ring, passing through 80 the upper ring, and secured at their upper ends in the block f³. At its upper end, above the collar, the handle is provided with a bead a' to prevent by any possibility the slipping of the collar from the handle at that end of 85 the same. A curved suspension-hook G is attached at its lower end to the block f³.

The collar, lamp-guard, and suspension-hook are preferably made of aluminium to 90 secure lightness.

To attach the guard, the screws f are partly unscrewed and their heads inserted through the keyholes e². The guard is then bodily turned so that the screw-shanks enter the narrow portions of the keyholes. The screws 95 are then tightened, holding the guard firmly in place on the collar. To remove the guard, the operation is reversed.

The tapering rubber handle protects the insulation of the conducting-wires from abrasion and destruction by the hand when in use, which would otherwise occur in handling the lamp, and it affords a larger and much more convenient grip for the hand. The ar-

- 5 arrangement of the tight-fitting collar opposite the socket secures a minimum thickness of soft rubber diametrically of the handle, and a degree of rigidity not otherwise obtainable is thereby secured for the lamp-guard and bulb. Water or other liquid is effectually prevented from reaching the lamp-socket by reason of the close contact of the contracted portion of the handle with the bulb.
- 10 10 My improved portable electric lamp is adapted for use in all situations partly or entirely inaccessible to exterior light and is of special use, for example, in inspecting or cleaning the interior of casks in breweries and boilers in boiler-works and other manufacturing establishments, &c.
- 15 Having thus described my invention, I claim as new and desire to secure by Letters Patent—
- 20 20 1. A portable electric lamp, consisting of a flexible handle provided with a bore for the conducting-wires, said handle being composed of a socket portion, a handle portion, and a tapering end portion, a lamp-socket in said
- 25 25 socket portion, an incandescent electric lamp in said socket, a collar extending around the socket portion of the handle, and a lamp-guard attached to said collar, substantially as set forth.
- 30 30 2. A portable electric lamp, consisting of a flexible handle provided with a bore for the conducting-wires, said handle being composed

of a socket portion, a contracted portion at the upper end of said socket portion, a handle portion, and a tapering end portion, a 35 lamp-socket in said socket portion, an incandescent electric lamp in said socket, a collar extending around the socket portion of the handle, and a lamp-guard attached to said collar, substantially as set forth. 40

3. A flexible handle for portable electric lamps, consisting of a socket portion at one end, a handle portion below the same, and a tapering end portion, said handle being provided with a bore for the conducting-wires 45 and being made in one integral piece of elastic material, substantially as set forth.

4. A flexible handle for portable electric lamps, consisting of a socket portion at one end, a contracted portion at the upper end of 50 said socket portion, a handle portion below the same, and a tapering end portion, said handle being provided with a bore for the conducting-wires and being made in one integral piece of elastic material, substantially 55 as set forth.

In testimony that I claim the foregoing as my invention I have signed my name in presence of two subscribing witnesses.

ARTHUR DRESCHER.
